DISPLAY DEVICE

Arthur J. Traumüller, Sr., Brooklyn, N. Y.

Application January 27, 1941, Serial No. 376,033

8 Claims. (Cl. 267—1)

This invention relates to display devices such as jewelry, watch, and other boxes, trays and the like, in which jewelry, watches and other articles are arranged on display or against displacement and accidental removal from the box, tray or the like, and more particularly the invention relates to a yieldable mounting for jewelry and other articles of the class described for attachment to boxes, trays and the like, to engage one or both ends of various articles in 10 yieldably retaining the articles in a box or on a tray against accidental displacement; and the object of the invention is to provide a mounting of the character described employing a mounting plate in which a rod is slidably mounted with means for securing one end of the coil spring arranged on said rod to one end portion of the plate and to other means for quickly and economically securing the other end of the spring to the rod to permanently unite said end of the spring to the rod; a further object being to provide means coupling the spring to the rod within the boundaries of the frame to form a guide and reinforcing member for the rod in its movement in said frame; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional view through a tray or container illustrating one adaptation of the invention with part of the construction broken away.

Fig. 2 is a bottom plan view of the yieldable article supporting device illustrated in detail in Fig. 1.

Fig. 3 is a partial section on the line 3—3 of Fig. 2.

Fig. 3a is a view similar to Fig. 3 showing the assemblage of the parts prior to their securing the spring and coupling to the rod.

Fig. 4 is a view similar to Fig. 3 showing another adaptation of the invention; and

Fig. 5 is a view similar to Fig. 1 omitting the box or tray and showing a modified form of construction.

In the art of mounting jewelry and particularly elongated pieces of jewelry such as chains,

bracelets, necklaces and the like, as well as wristwatches, in display or shipping boxes or upon display trays, it has been a common practice to use yieldable mounting members in the form of spring actuated pins arranged in some type or kind of mounting plate or support to engage at least one end of the jewelry or article to be supported, and in some instances, to engage both ends thereof. In mountings of this type and kind, the same are produced very economically in order to keep the cost down as much as possible. This is particularly true where the hardware is employed in connection with boxes which are ultimately disposed of. 15 While relatively simple forms of these devices have been made, the cost of assembling and otherwise producing such devices has made it difficult to supply the demand at an extremely reasonable price. To avoid these difficulties, I 20 have conceived a simple and economical form of yieldable mounting which, by reason of the construction thereof, the cost of assemblage and ultimate production of the device is materially decreased, while at the same time a more practical and efficient product is formed.

In Figs. 1 to 4 inclusive, I have shown one method of constructing devices of the kind under consideration, and in these figures, and in Figs. 1 to 3 inclusive, a single mounting unit is disclosed, whereas in Fig. 4, a dual pin mounting is illustrated.

To show the general adaptation and use of the invention, I have diagrammatically illustrated in Fig. 1 of the drawing at 10 a box or tray within which is arranged an article supporting sheet 11 of any suitable material which is usually provided with a facing 12 of velvet, silk or other finishing material to produce a neat and finished appearance in the box or tray 35 as well as to provide a desirable support for the jewelry, not only to protect the same but further to properly set off the jewelry arranged thereon. In the simpler or single form of device of this class; that is to say where a single yieldable article supporting hook 13 is employed, the 40 opposed end of the box or tray is provided with a stationary pin or hook 14 arranged in alignment with the hook 13.

The hook 13 forms part of what might be termed 50 a yieldable mounting unit 15 which comprises an elongated channeled plate 16 having downwardly turned end flanges 17 and 18, the plate also having prongs or spaced apertures 19 facilitating attachment of the plate to the under-surface of the sheet 11. The flanges 17 and 18 are provided

with apertures 20 to receive a sliding pin or rod 21, one end of which is bent upwardly and outwardly to form the hook 13. The other end 22 protrudes slightly beyond the flange or wall 18.

Arranged upon the rod 21 is a spring 33, the coils of which are closely wound so as to form a stop limiting movement of the hook end 13 in a direction away from the plate 16. In assemblage of the spring and pin with the plate 16, one end portion 24 of the spring is first passed over the flange 17 in alinement with the aperture 20 in said flange. That is to say, the flange is placed between one of the coils of the spring, after which the end portion 22 of the pin is passed through the aperture in the flange 17 through the spring 33, and an eyelet 25 is arranged on the pin at the other end portion 26 of the spring. Then, when the pin 21 is in proper position, pressure is applied to the end portion 26 of the spring to compress the coils of the spring onto the sleeve portion 27 of the eyelet 25 to partially imbed the eyelet in the pin as seen at 28 in Fig. 3 of the drawing to fixedly key and retain the eyelet against shifting on the pin 21, as well as to secure the spring to the eyelet. With the parts in this position, it will appear that the hook end 13 of the pin 21 may be moved inwardly or in the direction of the mounting plate 16 extending the spring in this operation. The abutment of the coils spring serves to check outward movement of the pin 13 with respect to the flanged wall 17.

In Fig. 4 of the drawing, a slight modification of the construction shown in Figs. 1 to 3 inclusive is illustrated; that is to say, two pins 29, 30, both substantially similar to the pin 21, are mounted side by side in flanged portions 31, 32 of a mounting plate 33 with springs 34 arranged thereon and secured to the respective pins as at 35 in the same manner as the attachment at 26 in Figs. 1 to 3 inclusive. It is also preferred that the attached portions 35 be arranged in common transverse alinement so that a single tool operation may simultaneously secure the springs to the rods as at 35. The pins or rods 29, 30 are also preferably offset as seen at 36 in order to maintain the outer hook end portions 37 thereof in common alinement.

A structure of this type and kind is adapted for use in boxes or trays to provide two yieldable article engaging hooks or couplings instead of the one fixed pin or hook 14 and the one movable hook 13 as in Fig. 1 of the drawing. It will of course be apparent that larger mounting plates may be employed; particularly when designed to support a multiplicity of articles. In such uses, any desired number of the individual pin or rod units may be arranged at one or both side portions of the mounting plate and spaced in a manner to suit the particular types and kinds of articles to be supported on the tray.

In Fig. 5 of the drawing, I have shown another adaption of my invention which differs from the structure shown in the other figures, primarily in the manner of attaching the inner end portion of the spring to the rod. In this construction, the mounting plate is indicated at 38, the angular flanges at 39 and 40, the pin is shown at 41, and the hook of the pin is indicated at 42. At 43 is shown the spring arranged upon the pin with one end 44 coupled with the flange 39 in the same manner as the attachment of the spring end 24 to the flange 17. Substituted for the eyelet 25 is a small and comparatively narrow U-shaped coupling 45 having outwardly projecting side flanges 46 and 47, over one of which, the flange 46, the

end portion 48 of the spring 43 is passed in the same manner as the attachment of the end 44 with the flange 39. After the pin or rod 41 has been passed through the apertures in all of the flanges 39, 40, 46, 47, and through the spring 43 when attached to the flanges 39, 46, that part of the pin or rod between the flanges 46 and 47 is kinked or offset as indicated at 49 in order to retain the coupling 45 against movement with respect to the rod; thus producing a result substantially similar to the compression or flattening of the spring around the eyelet as at 26 and 35.

It will also be noted that the crosshead of the coupling 45 is arranged in close proximity to the inner surface of the mounting plate 38 so that the coupling will act as a guide and reinforcement for the pin 41 in the sliding movement thereof in the flanges of the mounting plate.

With both forms of construction disclosed, it will appear that the assemblage of the parts becomes very simple and thus, material saving is effected in the production of devices of the kind under consideration, and furthermore, the production ratio is materially increased. It will also appear that by arranging the spring substantially within the boundaries of the end flanges of the mounting plate, the overall dimensions of the complete unit can be materially reduced, as after all, it is only essential to provide sufficient clearance between the hook end of the rod and the adjacent end wall or flange of the mounting plate to compensate for the predetermined movement of the rod within the plate. In like manner, the inner end of the rod need protrude beyond the other end wall or flange of the mounting plate sufficiently to prevent accidental displacement of the rod when the latter is in its normal extended position. Furthermore, the housing of the spring within the mounting plate serves to shield and guard the spring to prevent interference therewith and with the rod in the free operation of the rod. It will of course be apparent that the flanges or end walls of the mounting plates form what might well be termed bearings for supporting and guiding the pin or rod in its movement.

It is of course to be understood that while the invention has been described primarily for use in supporting or mounting articles of the type and kind under consideration, the unit as a product of manufacture may be used for many purposes; that is to say, wherever it is desirable to yieldably support a protruding member of any type or kind, particularly in the construction of economical types of yieldable mountings or catch devices.

Having fully described my invention, what I claim as new and desire to secure by Letters Patent is:

1. A yieldable mounting unit for articles of the class described, said unit comprising a mounting plate having apertured end walls for forming bearings, an elongated plunger slidably mounted in the bearings of said plate, a projecting article engaging element at one end of said plunger, a coil spring encircling the plunger intermediate said end walls, one end of the spring being retained against movement with respect to the end wall adjacent said article engaging element, and means fixedly securing the other end of the spring to said plunger intermediate said end walls with said last named means spaced from the second of said end walls sufficiently to provide predetermined movement of the plunger in the direction of the last mentioned wall against the action of said spring.

2. A yieldable mounting unit for articles of the class described, said unit comprising a mounting plate having apertured end walls for forming bearings, an elongated plunger slidably mounted in the bearings of said plate, a projecting article engaging element at one end of said plunger, a coil spring encircling the plunger intermediate said end walls, one end of the spring being retained against movement with respect to the end wall adjacent said article engaging element, means fixedly securing the other end of the spring to said plunger intermediate said end walls with said last named means spaced from the second of said end walls sufficiently to provide predetermined movement of the plunger in the direction of the last mentioned wall against the action of said spring, said spring limiting the movement of the plunger in the opposite direction, and the means securing the spring to the plunger comprising an element arranged on the plunger and to which the spring is attached.

3. A yieldable mounting unit for articles of the class described, said unit comprising a mounting plate having apertured end walls for forming bearings, an elongated plunger slidably mounted in the bearings of said plate, a projecting article engaging element at one end of said plunger, a coil spring encircling the plunger intermediate said end walls, one end of the spring being retained against movement with respect to the end wall adjacent said article engaging element, means fixedly securing the other end of the spring to said plunger intermediate said end walls with said last named means spaced from the second of said end walls sufficiently to provide predetermined movement of the plunger in the direction of the last mentioned wall against the action of said spring, said spring limiting the movement of the plunger in the opposite direction, the means securing the spring to the plunger comprising an element arranged on the plunger and to which the spring is attached, and said element comprising an eyelet arranged within said end of the spring and upon which the spring end is compressed.

4. A yieldable mounting unit for articles of the class described, said unit comprising a mounting plate having apertured end walls for forming bearings, an elongated plunger slidably mounted in the bearings of said plate, a projecting article engaging element at one end of said plunger, a coil spring encircling the plunger intermediate said end walls, one end of the spring being retained against movement with respect to the end wall adjacent said article engaging element, means fixedly securing the other end of the spring to said plunger intermediate said end walls with said last named means spaced from the second of said end walls sufficiently to provide predetermined movement of the plunger in the direction of the last mentioned wall against the action of said spring, said spring limiting the movement of the plunger in the opposite direction, the means securing the spring to the plunger comprising an element arranged on the plunger and to which the spring is attached, and said element comprising a U-shaped member providing spaced bearings for said plunger, the spring being secured to one of the bearings and the plunger being offset intermediate said bearings.

5. An article of manufacture of the class

described comprising a mounting plate having flanged end walls apertured to form guide bearings for a plunger pin, a plunger pin mounted in said bearings, a coil spring arranged upon the pin intermediate the bearings with one end of the spring secured to one of said bearings, the other end of the spring being arranged in spaced relation to the other of said bearings, a coupling element arranged on the pin at the last named end portion of said spring, and means securing the spring to said coupling element and for retaining the element against movement on said pin, and an article engaging part on the end of said pin adjacent said first named bearing.

15 6. An article of manufacture of the class described comprising a mounting plate having flanged end walls apertured to form guide bearings for a plunger pin, a plunger pin mounted in said bearings, a coil spring arranged upon the pin intermediate the bearings with one end of the spring secured to one of said bearings, the other end of the spring being arranged in spaced relation to the other of said bearings, a coupling element arranged on the pin at the last named end portion of said spring, said coupling element comprising an eyelet arranged on the pin and extending into the end coils of the spring, and said end coils being compressed on the eyelet and the eyelet onto the pin in uniting the spring and eyelet against movement relatively to the pin.

7. An article of manufacture of the class described comprising a mounting plate having flanged end walls apertured to form guide bearings for a plunger pin, a plunger pin mounted in said bearings, a coil spring arranged upon the pin intermediate the bearings with one end of the spring secured to one of said bearings, the other end of the spring being arranged in spaced relation to the other of said bearings, a coupling element arranged on the pin at the last named end portion of said spring, and said element comprising a U-shaped part having spaced flanges arranged longitudinally of the pin, the spring engaging one of said flanges and the pin being offset intermediate the flanges in retaining the element against movement longitudinally of said pin.

8. An article of manufacture of the class described comprising a mounting plate having flanged end walls apertured to form guide bearings for plunger pins, plunger pins mounted in said bearings in spaced relation to each other, a coil spring arranged on each of said pins substantially within the limits of said plate, one end of one spring being attached to one of said bearings and the end of the other of said springs being attached to the other of said bearings, inner ends of said springs being disposed in substantially the same transverse alignment in overlapped relationship to each other, means on the pins engaging the inner ends of said springs for securing said ends against movement longitudinally of the pins, said last named means being disposed substantially centrally between the bearings of said plate, and the ends of said pins protruding outwardly beyond the bearings, each having coupling members for attachment with articles to be engaged thereby.
